UNITED STATES PATENT OFFICE.

FOREST CHENEY, OF CHICAGO, ILLINOIS, ASSIGNOR, BY MESNE ASSIGNMENTS, TO
CHENEY TALKING MACHINE COMPANY, OF CHICAGO, ILLINOIS, A CORPORATION
OF ILLINOIS.

SOUND-REPRODUCING MACHINE.

1,287,881.

Specification of Letters Patent.

Patented Dec. 17, 1918.

Application filed March 8, 1913. Serial No. 752,861.

To all whom it may concern:

Be it known that I, FOREST CHENEY, a citizen of the United States, and a resident of Chicago, in the county of Cook and State of Illinois, have invented certain new and useful Improvements in Sound-Reproducing Machines, of which the following is a full, clear, and exact specification.

My invention is concerned with certain improvements in sound-reproducing machines that are designed to make the adjustment of the needle easier than is possible with these devices as they are now constructed.

My improved machine includes a breech-loading needle-holder, together with a gage by which the needles can be accurately adjusted without any expert knowledge of how the adjustment should be effected.

My improved machine also embodies a novel construction of the needle-holder and needle-arm, and its connections with the sound box, as will be hereinafter described.

To illustrate my invention, I annex hereto drawings, in which the same reference characters are used to designate identical parts in all the figures, of which,—

Figure 1 is a top plan view of a portion of a machine embodying my invention;

Fig. 2 is a side elevation of the sound box resting upon the needle-adjusting gage;

Fig. 3 is a detail in section on the line A—A of Fig. 1.

Heretofore, the set screw 41 has been threaded through the needle-holder 31 so that the set screw stands at right angles to the plane of the diaphragm 10. As a result of this location of the screw, with the vibrations of the needle to and from the end of said screw, the fulcrum of the needle was changed with the change of direction of the vibration. In moving in one direction, the needle would have its fulcrum against the lower edge of the aperture by which it enters

the needle-holder 31, and in moving in the other direction it would have its fulcrum against the end of the set screw 41. In my improvement, I place the set screw 41 in a plane parallel to the diaphragm, and as a result, the screw does not act as the fulcrum for the needle at any point, and there is no change in the fulcrum point of the needle as it vibrates from one side to another, and there is no consequent distortion of the tone which results with the old arrangement.

Referring to Figs. 1, 2 and 3, it will be seen that I form or place on the cabinet, adjacent to the disk-holder, a guide rail 42, which stands at the proper angle so that as the tone arm 23 is swung, the sound box can rest thereon, as shown in Fig. 3. Adjacent the inner end of this guide rail 42, I place an aperture 43 in the table, and when the set screw 41 is unloosened, the discarded needle can be tapped, and will fall out of the holder 65 through the aperture 43 into a suitable receptacle. It will be understood that the aperture 43 itself might constitute the receptacle. Beyond the aperture 43, I place a series of steps 44, 45 and 46, which are adapted, when a needle of the proper grade is dropped through the aperture 36 in the needle-holder, to cause said needle to come to rest on the surface at the proper adjustment for the needle of that grade, when the needle holder is moved to overlie the proper step. The set screw is then tightened, and the needle will then be properly adjusted to cooperate with the record 40, which, of course, has its upper surface in a certain 80 definite relation to the surfaces of the steps 44, 45 and 46. These steps can also be used to give an extraordinary set to a needle, if desired.

It will be noted that the needle holder 31 has a needle aperture extending therethrough of uniform bore throughout its length so that the needle can be inserted from the top of the holder making it "breech-loading."

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

What I claim as new and desire to secure by Letters Patent of the United States, is:

1. In a sound-reproducing machine, a sound box, a needle holder carried by said sound box, an element for supporting said sound box in inoperative position, and a second element adapted to engage the point of a needle when said needle is in said needle holder to position said needle therein, one of said elements being stepped to permit adjustment in the length of the needle projecting from said holder.

2. In a sound-reproducing machine, a sound box, a needle holder carried thereby, said needle holder having a bore therethrough adapted to receive a needle mounted in its upper end, means for clamping the needle in said bore, and means separate from said needle holder upon which the end of the needle rests for properly positioning needles of different grades in said bore.
3. In a sound-reproducing machine, a breech-loading needle holder, and needle-positioning means comprising a plurality of relatively fixed parts, said needle holder and said means being relatively movable whereby any one of said parts may be caused to aline with said needle holder and engage the point of a needle to position the same in said holder.
4. In a sound-reproducing machine, a tone-arm, a sound box secured to said tone arm, a breech-loading needle holder carried by the sound box and adapted to hold the needle for actuating the diaphragm, and a stepped plate having a flange to support said sound box when the latter is in the proper relative position, said stepped plate and sound box being relatively movable and said needle holder being adapted to aline with a desired step of the plate for the purpose of adjusting the needle in the desired position in said holder.
5. In a sound-reproducing machine, the combination with a tone-arm, of a sound box secured thereon, a breech-loading needle holder mounted on the sound box, and a stepped plate having a supporting rail for said sound box, said tone-arm being movable to bring the sound box on to the supporting rail for the purpose of positioning a needle in the holder by means of one of the steps of said plate.
6. In a sound-reproducing machine, the combination with a tone-arm, of a sound box secured thereon, a breech-loading needle holder mounted on the sound box, a stepped plate having a supporting rail for the sound
- box, said stepped plate being adapted for use in positioning a needle in the holder, said tone-arm being movable to bring the sound box onto the supporting rail, and a discharge aperture adjacent the stepped plate to receive needles discharged from the needle holder.
7. In a sound-reproducing machine, a tone-arm, a needle holder carried by said tone-arm, a fixed support adjacent the position normally occupied by the tone-arm, a stepped plate mounted on the fixed support, said tone-arm being movable to operative position with respect to said stepped plate, and means to support the tone-arm in said position adjacent the stepped plate, said stepped plate having a plurality of steps adapted to aline with the needle holder, whereby said steps may be caused to co-act with the point of a needle to locate the same in the proper position in said needle holder.
8. In a sound-reproducing machine, a needle holder having a bore therein adapted to receive a needle, means to clamp the needle in said bore, a member by which the needle holder is carried, and graduated means with which said needle holder may be brought into alinement for the purpose of properly positioning needles of different grades in said needle holder.
9. In a sound-reproducing machine, a needle holder having a bore therethrough to receive a needle, and a needle-positioning means separate from said holder having a plurality of parts each adapted to aline with the bore of the needle holder when the latter is in an inoperative position to engage an end of a needle and position the same in said bore.

In witness whereof I have hereunto set my hand and affixed my seal this tenth day of February, A. D. 1913.
